TIPTING HEAD PRESS

Stewart Bolling, Cleveland, Ohio

Application May 9, 1947, Serial No. 746,989

6 Claims. (Cl. 18—16)

1

This invention relates to a tilting-head molding press, that is designed primarily for pressure curing or vulcanizing sound-reproducing records from shellac, rubber, or plastic bases.

Machines of this type customarily embody the use of upper and lower mold members between which the material to be molded under pressure is received.

In the art, presses of this type have in general been of the type embodying a spider construction, and have been exceedingly difficult to cast, and to machine with the required accuracy. In this connection, accuracy of operation is an important requisite of such a press, the ultimate aim in construction of such a press being to provide molds which will register perfectly when closing, and which will remain in full register as pressure is applied thereto.

In hinged head or tilting head presses, the tilting head, which is one of the mold members, has heretofore required, by reason of the very nature of this type of construction a working or sliding clearance as the locking member of the press, and this has caused movement as the molds close, preventing the molds from registering perfectly.

An important object of this invention, therefore, is to provide a tilting head molding press wherein the tiltable locking head embodies a novel construction wherein perfect register between the mold members is obtained before the molds begin to close. Additionally, it is an important object of the invention to embody in said construction, a means for strengthening the locking action by spreading it over a wider area than has heretofore been the case with side frame plates embodied in the press being retained in exact predetermined relation to each other and to the locking head, with full preventive means afforded in the construction against spreading of the plates when the lock is applied. It is a further important object to meet the above purposes of the invention, and yet to provide a locking head that will be capable of being locked or unlocked with unusual ease.

Another important object of the invention is to provide a side frame plate construction cooperating with the locking head, whereby machining of such plates in construction of presses can be permitted in multiple, that is, a group of plates can be machined together, rather than separately, as heretofore.

Still another object of the invention is to provide a press of this character in which a single spring pull-back is used with an equalized cable,

2

constituting means for returning a movable lower mold member to its normal position.

With the foregoing and other objects in view which will appear as the description proceeds, the invention consists of certain novel details of construction and combinations of parts, hereinafter more fully described and pointed out in the claims, it being understood that changes may be made in the construction and arrangement of parts, without departing from the spirit of the invention as claimed.

Referring to the drawings.

Figure 1 is a front elevational view of a molding press constructed in accordance with the invention, a portion of a spring housing embodied in the invention being cut away for the purpose of showing the details of the pull back means.

Figure 2 is a top plan view, there being a portion of a clamping bar embodied in the locking head cut away, to show details of construction.

Figure 3 is a side elevational view of the upper portion of the press, showing the locking head in open position.

Figure 4 is a similar view, partly in side elevation and partly in vertical section, showing the locking head in locked or closed position.

Figure 5 is an enlarged view of the locking head construction, taken on line 5—5 of Figure 2.

Referring to the drawings in detail, the reference character 5 designates opposed angle members, having openings 6 for foundation bolts, whereby the press may be securely anchored in proper position. The angle members 5 are immovably secured by any well-known means to the lower ends of a pair of opposed side frame plates 7, that constitute the main frame of the press.

As clearly shown in Figure 1, the side frame plates 7 are erected so as to constitute vertical side supports of the press, and cooperate at their upper ends with the locking means embodied in the invention for locking the tilting upper mold member in proper position. The side frame plates, as will be noted, extend from top to bottom of the press, and are disposed in spaced parallel relation to each other.

In a construction as illustrated and described herein, the side frame plates 7 will originally be in the form of flat plates of suitable thickness. It will be seen, therefore, that they can comprise hot rolled plates, ground on their inner faces in groups, with their top edges turned to contour, front and back edges planed, and their bottoms planed square. Such a construction, as is believed apparent, permits machining with ease,

an unusually desirable feature in a press of this type.

Through bolts 8, having stud ends 9 of reduced diameter which are received in suitable openings in the side frame plates 7, cooperate with nuts 10 to connect the plates securely together near their lower ends.

Immovably mounted between the plates 7 above the bolts 8 is a cylindrical ram casing 11, which can be cast integral with mounting plates 12 and 13 and with a down-curved bottom plate 14.

The ram casing 11 receives for slidable movement therein the movable ram 15. The ram casing 11 is itself held immovable relative to the side frame plates 7, as by nuts 16 threaded on studs projecting from the mounting plate 12, while opposed grooves 17 can be formed in the inner faces of the plates 7, receiving the side edges of the mounting plate 13.

A pipe 18, leading to a source of pressure (not shown), admits fluid, air, or the like, under pressure between the lower end of the ram 15 and the bottom plate 14 of the ram casing, whereby to thrust the ram 15 upwardly in molding operations.

Carried on the upper end of the ram 15 is a moving table 19, having a flat upper surface, this constituting the lower mold member of the press. Table 19 is fixedly secured to the ram 15, as by a weld 20 shown in Figure 5, or the like. Guide members 21 on the corners of the moving table 19 slide on the front and back edges of the plates 7, so that the moving table 19 may be maintained in proper alignment relative to the plates, during the molding operation.

As described above, the moving table 19 carried by ram 15 moves upwardly under pressure, in molding the material received by the press. When, however, the pressure is exhausted, at the completion of the molding operation, means embodied in the invention serve to return the moving table 19 automatically to a normally withdrawn position.

This means comprises hooks 22 secured to the bottom face of the moving table 19, to which are secured both ends of an equalizer cable 23. Cable 23 is extended downwardly from its ends through suitable openings in the ram casing 11, which openings are formed in the mounting plates 12 and 13, and in which the cable 23 may freely slide. Below the ram casing 11, the cable 23 passes around guide pulleys 24 on opposite sides of the press, these being secured to the inner faces of the plates 7 by any well-known and suitable means.

Intermediate its ends, and at a central point relative to the space between the plates 7, the cable 23 passes around a sliding plug 25, engaging the lower end of a vertically disposed spring 26, contained in spring housing 27, that is fixedly secured at its upper end, as at 28, to the bottom plate 14 of the ram casing 11.

Opposed slots 29 are formed in the housing 27, to provide a sliding clearance for the plug 25 carrying the cable 23. By reason of this construction, it is seen that when the moving table 19 moves upwardly under the application of pressure, the equalizer cable 23 will carry the plug 25 upwardly, compressing the spring 26. When, however, the pressure is relieved, the spring 26 will expand, returning plug 25 to its low position, and automatically pulling back the moving table 19.

I also provide in my invention a tiltable locking head, which has been designated generally by

the reference character 30. The body of the head 30 may, as will be apparent, be cast integral, with a flat bottom, constituting an upper mold member 31, side walls 32 the outer surfaces of which engage the inner faces of the plates 7 adjacent the upper ends of the plates, and a plurality of transverse ribs 33, which serve to reinforce the tilting head 30, and some of which, additionally, comprise bearing members for a locking means, as will hereinafter become apparent.

To the upper surfaces of the opposed side walls 32 are secured spaced parallel clamping bars 34, which span the side walls 32, and which may be connected to the side walls by means of bolts 35. Under certain conditions, it will be desirable to parallel the upper mold member 31 with the moving table or lower mold member 19, and this can be effected by means of adjusting the locking bars 34 relative to the tilting head 30, by means of the bolts 35, there being compression washers 36 in the form of rubber O rings, interposed between the heads of the bolts and the upper surfaces of the clamping or locking bars 34.

As particularly well shown in Figure 1, the ends of the spaced parallel clamping bars 34 extend beyond the plates 7, and are downwardly flanged as at 37 so as to engage the outer surfaces of the upper ends of the plates, whereby to prevent the plates 7 from spreading under the action of the locking means to be described hereinafter.

As indicated above, the head 30 is of a hinged or tiltable type, relative to the press proper and the hinge means embodied in the invention are shown in Figures 2 through 4 inclusive. Opposed plates 38 are rigidly mounted on the rear edges of the side walls 32 and from each of these is downwardly extended a hinge arm 39, these being immovable relative to the plates 38 and to the tilting head 30.

At their lower ends, the hinge arms 39 carry circular enlargements 40, and in these is mounted a hinge pin 41, having reduced ends carried in open grooves formed in the upper surfaces of opposed brackets 42, that are fixedly connected to, and extend rearwardly from, the side frame plates 7.

Fixedly connected at one end to the circular enlargements 40 are weight-supporting members 43, that extend rearwardly from said enlargements, and carry depending counter-weights 44 on their other ends, the counter-weights 44 being pivotally hung thereon, as shown at 45. This construction permits the tilting head 30 to be swung open or closed when unlocked, with a minimum of effort on the part of the operator.

Additionally, it may be noted that it would be well within the spirit of the invention, and sufficiently obvious as not to require illustration, that in place of counter-weights 44, a piston could be secured to the free ends of the members 43, working under pressure in an air cylinder or the like, for the purpose of swinging the tilting head 30 open or closed.

The locking means, cooperating between the tilting head 30 and plates 7 for the purpose of locking the head in exact immovable position for molding operations, embodies first the formation of opposed slots or recesses 46 that are ground in the outer surfaces of the respective side walls 32 of the tilting head 30, extending from end to end thereof. These receive locking lugs 47 which are formed correspondingly to the slots 46, and extend from end to end thereof. The locking lugs 47 are adapted to swing outwardly

from their slots 46 for the purpose of locking the tilting head 30, this position being shown particularly in Figure 5, the lugs swinging into opposed angular recesses 48 formed in the inner faces of the plates 7.

As clearly shown in the drawings, the lower longitudinal edges of the locking lugs 47 are transversely curved, as shown at 49, these curved lower edges being seated in correspondingly depressed lower walls of the slots 46, so that the upper portions of the locking lugs 47 may be swung outwardly out of the slots. As shown at 50, the outer surfaces of the locking lugs are ground to provide angular surfaces corresponding to the formation of the recesses 48 in the plates 7, so as to permit an effective locking grip therewith.

Thus, it is seen that when the locking lugs are swung into the position shown in Figure 5, their upper edges engage the upper walls of the recesses 48 in the side plates 7, while their lower edges remain in engagement with the lower walls of the slots 46 of the tilting head 30. As a result, the tilting head 30 is immovably secured in locking relation to the plates 7, and is immovable against upward thrust exerted by the ram 15. At the same time, the plates 7 are immovably held against lateral spreading by the grip of the flanged ends 37 of the clamping bars 34, also carried by the tilting head 30.

Opposed ears 51 extend inwardly toward each other from the inner surfaces of the locking lugs 47, these being received in opposed openings 52 formed in the side walls 32, and communicating between the slots 46 and the space between the side walls. Connecting rods 53 are respectively pivotally joined at one end to the ears 51, and at their other ends are pivotally connected as at 54 to a wheel 55, carried by shaft 56 journaled, as particularly well shown in Figure 4, in adjacent ribs 33. The pivotal connections 54, as observed in Figure 5, are disposed at opposite sides of the axis of the wheel.

The shaft 56 is extended beyond the front end of the tilting head 30, and is there provided with a crank 57, which as shown, may be a hand crank, although obviously, other means can, within the spirit of the invention, be employed to rotate the shaft. Rotation of the shaft 56 in one direction serves to withdraw the locking lugs 47 into the slots 46, unlocking the tilting head 30, while rotation in the opposite direction swings the locking lugs 47 outwardly into locking position.

A latch means is embodied in the invention for the purpose of retaining the wheel 55 in the position to which it is rotated, when moving the locking lugs 47 into fully locking engagement with the plates 7. A hand lever 58 has its lower end fulcrumed at 59 to the upper mold member 31 of the tilting head 30, the lever being pivotally joined intermediate its ends to one end of a latching arm 60, which is slidable in suitable openings in the ribs 33, and received as to its other end in an opening 61 formed in the wheel 55. Intermediate its ends, the rod 60 is provided with a coiled spring 62, which is adapted to urge it continually forward, so as to retain the rod 60 in opening 61. The forward movement of the rod 60 is limited by collar 63 engaging one surface of one of the ribs 33. When the locking lugs 47 are withdrawn into the recesses 46, it is a preliminary operation to so withdrawing them, as will be seen, to first withdraw rod 60 from the opening 61. After the wheel 55 has been turned, the inner end of the rod 60 will simply engage

the surface of the wheel 55, and will be out of register with the opening 61 formed therein.

The construction which I have illustrated and described herein is one which permits the upper and lower mold members to be brought into proper register before the mold begins to close. Should necessary adjustment be needed to bring the molding surfaces of these members into parallel relation, so that they will lie in fully parallel planes, adjustment of the upper mold member 31 can be permitted by threading of the bolts 35 at the four corners of the tilting head, or the threading of any one or more of these

15 Once the head is locked, it is immovable, and the side plates 7 are retained fully against lateral spreading. It is to be noted, in this connection, that the position of the tilting head 30 relative to the side frame plates 7, when it is 20 brought into position for molding operations, is in no sense determined by its hinge connection to the side plates. The final relation of the parts of the hingeable connection between the tilting head and the side plates is determined only 25 after the head has been brought into locking position, and locked. Thus, the relation of the head to the side frame plates is actually determined by the clamping bars 34 carried on the head, in the final analysis, and not by the hinged connection.

30 What is claimed is:

1. In a tilting head molding press the combination, with opposed side frame plates, of a head hinged at one end to the side frame plates, an upper mold member on the head, and means for transmitting thrust exerted against the head directly to the side frame plates, said means comprising locking lugs pivotally mounted in the opposed side walls of the head, there being slots 35 formed in the respective side walls normally receiving the lugs, the side frame plates having opposed lug-receiving recesses formed in their inner surfaces, means for swinging the lugs to a locking position with the recesses of the side 40 frame plates, the recesses being entirely filled by the lugs, and means for retaining the lugs in said locking position.

2. In a tilting head molding press the combination with opposed side frame plates of a head hinged at one end thereto, there being opposed slots formed in the side walls of the head, locking lugs carried in the slots, said lugs having lower portions pivoted in the slots, means connecting the lugs for simultaneous inward and outward swinging movement relative to the head, there being opposed recesses formed in the inner surfaces of the side frame plates in which the upper portions of the lugs are received when swung outwardly, the lower portions remaining 50 in the slots, and means for retaining the lugs in the positions to which they are swung outwardly into the recesses.

3. In a tilting head molding press including a lower mold member, the combination, with spaced apart side frame plates of a tilting head, constituting an upper mold member, hinged at one end to the side frame plates and proportioned to fit therebetween, means carried by the side walls of the head cooperating between the head and side frame plates proportioned to lock the head to the side frame plates, said means adapted to receive all thrust exerted against the head by the lower mold member and transmit it directly to the side frame plates, and clamping 60 bars adjustably connected to the head engage-

able with the side frame plates, said bars adapted to prevent lateral spreading of the plates under said thrust.

4. In a frame and tilting head construction for a molding press, side frame plates on the frame, a head hinged at one end to the plates, side walls on the head having opposed slots in their outer surfaces, the side frame plates having opposed recesses in their inner surfaces communicating with the respective slots, locking lugs swingably mounted in the slots, means for simultaneously swinging the lugs into and out of the recesses, the lower portions of the lugs remaining in the slots, means for retaining the lugs in positions to which they are swung into the recesses, and clamping bars adjustably connected to the head, and proportioned for clamping engagement with the side frame plates.

5. In a tilting head molding press, the combination of opposed side frame plates having transversely disposed grooves extending fully across their inner surfaces, a head hinged at one end to the plates for downward swinging into the space therebetween, means on the head engageable with the plates on downward swinging of the head for limiting said downward swinging, elongated lugs extending the length of the respective side walls of the head and having their lower portions pivoted within said side walls, the upper portions of the lugs adapted to be swung into the grooves of the plates, and means carried by the head adapted to swing the lugs

simultaneously into and out of the recesses, said lugs adapted to receive thrust exerted upwardly against the head for transmission of said thrust from the opposed side walls of the head to the opposed plates.

5 6. In a tilting head molding press, the construction as set forth in claim 5, and said means for limiting downward swinging movement of the head comprising clamping bars mounted on the head and having end portions projecting beyond opposite sides of the head to engage the plates on downward swinging of the head, said end portions being formed with downturned end flanges adapted to overlie the outer surfaces of the plates to prevent lateral spreading of the plates.
